[57] **CLAIM**

The ornamental design for a bottle with triangular surfaces, as shown and described.

DESCRIPTION

FIG. 1 is a front elevation of a bottle with triangular surfaces showing my new design, the rear elevation is a mirror image thereto except for the conventional screw threading on the bottle neck;

FIG. 2 is a top view thereof;

FIG. 3 is a left side elevation thereof; the right side elevation is a mirror image thereto except for the conventional screw threading on the bottle neck; and,

FIG. 4 is a bottom view thereof.
